UNITED STATES PATENT OFFICE.

LOUIS COHEN, OF CAMBRIDGE, MASSACHUSETTS.

SYSTEM OF DISTRIBUTION FOR OSCILLATORY ELECTRICAL CURRENTS.

1,123,098.

Specification of Letters Patent. Patented Dec. 29, 1914.

Application filed December 14, 1912. Serial No. 736,875.

To all whom it may concern:

Be it known that I, LOUIS COHEN, a citizen of the United States, residing at Cambridge, in the county of Suffolk and State 5 of Massachusetts, have invented certain new and useful Improvements in Systems of Distribution for Oscillatory Electrical Currents, of which the following is a specification.

10 This invention relates to a system of distribution for oscillatory or alternating electrical currents, and has particularly in view a means for distributing currents of that character from one circuit to another in 15 such a manner as to provide a system of great flexibility, while at the same time securing an extremely "stiff" working circuit possessing great utility in its application to wireless signaling.

20 While the invention is of special utility in its application to wireless signaling, it is useful in any work where high-frequency alternating currents are employed and it is desirable to provide and maintain conditions which cause the working circuit to be 25 delicately sensitive and responsive only to currents of a definite frequency transmitted thereto from the supply circuit. Accordingly, the distinctive features of the invention 30 may best be explained by brief reference to the general conditions prevailing in wireless telegraph systems as ordinarily practiced. In this connection, however, it is only necessary to compare the present in- 35 vention with the ordinary and usual means employed in wireless telegraph systems for maintaining electrical communication between the two oscillating circuits. It is well known that in the use of high frequency 40 oscillatory currents, damped or undamped, for wireless signaling either in transmitting or receiving signals, two oscillating circuits are employed to secure operative conditions, and these two circuits are main- 45 tained in electrical communication, electro- magnetically, by means of a transformer, and it is the primary object of the present invention to entirely eliminate the use of a transformer for that purpose between two 50 oscillating circuits, and to substitute there- 55 for another form of coupling which not only accomplishes all of the electrical functions of the transformer in a different manner, but at the same time secures improved results in the general flexibility of the system and through the stiffening of the work-

ing circuit that is not possible of attainment through the use of an electromagnetic coupling, such as provided for by the transformer.

The primary object of the invention as above indicated is realized by maintaining electrical communication between two electrical circuits for oscillatory or alternating currents through the medium of an electrostatic coupling, as distinguished from an electromagnetic coupling. A comprehensive understanding of this electrostatic coupling as a means of providing electrical communication between two circuits of the character referred to can best be understood by reference to the accompanying drawings, in which—

Figures 1 and 2 are diagrams schematically showing the general arrangement of 70 two oscillating circuits coupled together electrostatically, as contemplated by the present invention. Fig. 3 is a diagrammatic illustration of the invention in its application to the receiving set of a wireless 75 telegraph system. Fig. 4 is a diagrammatic view illustrating a combination of electrostatic and electromagnetic couplings for the receiving set of a wireless telegraph system. Fig. 5 is a diagram illustrating an applica- 80 tion of the invention to the sending set of 85 a wireless telegraph system.

Referring specifically to the embodiments of the invention illustrated and suggested in the drawings, it will be observed that in 90 Fig. 1 of the drawings, the numeral 1 designates a source of oscillatory electromotive force, such for instance as an alternator, an arc, or an induction coil, the same being included in what may be termed the 95 supply or generating circuit *a*, while the working circuit to be operated may be generally indicated by the reference letter *b*. In the said illustration of Fig. 1 of the drawings, the circuit *a* includes 100 a resistance 2, an inductance 3, and a variable tuning condenser 4, while the other circuit *b* likewise includes a resistance 5, an inductance 6, a variable tuning condenser 7, and the electrical instrument de- 105 vice or apparatus, designated by 8 which is intended to be operated by the electrical im- 110 pulses or currents transmitted to the circuit *b* from the circuit *a*. These two circuits are electrostatically coupled by means of a variable condenser 9 of relatively small capacity, said coupling necessarily including suitable

leads *c* and *d*. This electrostatic coupling is the principal and distinguishing feature of the present invention, as hereinbefore indicated. It is proposed to arrange the constants of the two circuits so that the sum of the capacities 9 and 7, multiplied by the inductance 6 is equal numerically to the product of inductance 3 and capacity 4, and if the source of E. M. F. (1) produces a forced oscillation of a definite frequency, then both systems must be adjusted to be in resonance for that particular frequency. The condenser 9, which is the coupling condenser, must be made relatively small, about 1/50 to 1/10 of the capacity 7, in which case we get a current flow in circuits *a* and *b*. If the inductance 6 or the capacity 7 is changed somewhat, the current in the circuit *b* will be reduced, while the current in the circuit *a* is not affected; in other words, the said two circuits are independent in the same sense as the two circuits of an electromagnetically coupled system, and it will also be understood that the value of the coupling capacity 9 to be used depends largely on the frequency and also to some extent on the other electrical constants, which however is a factor that can readily be determined, and has been determined, mathematically.

The arrangement, schematically shown in Fig. 2, is exactly the same as that of Fig. 1 of the drawings, excepting that in Fig. 2 the condenser 4 and the inductance and resistance 3 and 2 are interchanged, and it will, therefore be obvious that the arrangement of circuits shown in Fig. 2 will operate in exactly the same way as the arrangement of circuits shown in Fig. 1. However, it may be noted at this point that the current in the elements 6, 5 and 7 of circuit *b* will be approximately opposite in phase, that is the current passing through the coupling condenser 9 will be approximately the difference of the currents in 6, 5, and 7 respectively. Consequently, while a very small current passes through the small coupling condenser 9 we may have fairly large currents in the circuit *b*.

In Fig. 3 of the drawings, the new electrostatic coupling is shown in its application to the receiving set of a wireless telegraph system. In this diagram, the letter *a* may still designate generally what has been termed the supply or generating circuit, and the letter *b* the working circuit including the various branches and elements of the latter. In said illustration of Fig. 3, 10 designates the antenna, 11 a loading inductance coil, and 12 the ground, thus completing the supply circuit. Included in the general working circuit *b* is the inductance 13, a variable tuning condenser 14, a large condenser 15 generally called a stopping condenser, the detector 16, and the receiving telephone 17, the said stopping condenser having the func-

tion of preventing the direct currents generated in the detector 16 from being shunted through the internal circuit *b'*, 13, and compelling them to pass through the telephone 17. When an electromagnetic wave of the incoming signals acts on the antenna, it generates a current in the antenna circuit *a* which is transmitted through the electrostatic coupling 9, *c*, *d*, to the oscillating circuit *b'*, 13, 14, and sets it in oscillation electrically. The energy of this oscillating circuit is gradually absorbed by the detector 16 which causes the signals to be indicated in the telephone.

As herein indicated, Fig. 4 of the drawings shows an arrangement adapting the invention to the receiving set of a wireless telegraph system wherein the electrostatic coupling feature is combined with an electromagnetic or transformer coupling. In this illustration, circuits and elements corresponding to circuits and elements in Fig. 3 are correspondingly numbered, in each case the electrostatic coupling consisting of the small condenser 9 and the leads *c* and *d*. However, in the combination shown in Fig. 4, the tuned circuit designated by *e* and including a tuning condenser 18 is coupled electrostatically to the antenna circuit through the coupling condenser 9, and the tuned circuit designated by *f* which includes a tuning condenser 19 is coupled electromagnetically to the tuned circuit *e* through the transformer 20. In this arrangement, shown in Fig. 4, that portion of the circuit which may still be referred to as the main working circuit *b* includes the stopping condenser 15, the detector 16, and the telephone 17. The said arrangement shown in Fig. 4 of the drawings gives remarkably sharp tuning and is therefore very effective in the elimination of all disturbances generally caused by other signals of different frequencies.

In Fig. 5 of the drawings is suggested an application of the invention to the sending set of a wireless telegraph system. In this arrangement, what may still be characterized generally as the supply or generating circuit, is designated by the letter *a* while in this instance the working circuit *b* is the antenna circuit consisting of the antennae 10^a, the coil 11^a and the ground connection 12^a. These two circuits are electrostatically coupled by the same electrostatic coupling already described, namely by the variable condenser 9 of small capacity and the leads *c* and *d*. Referring further to the details of the circuit shown in Fig. 5, 21 designates the leads from a high potential source, 22 the spark gap, 23 a variable condenser, and 24 an inductance. With this arrangement of circuits in the sending set of a wireless system, when the condenser 23 is charged to the critical point or to its maximum poten-

tial, depending on the length of the gap 22, a spark occurs in the said gap, thereby short-circuiting the circuit 22, 23 and 24, whereupon the condenser 23 discharges itself 5 through the inductance 24, when the resistance of the circuit is small as is usually the case, oscillations are set up in the circuit. If the constants of the antenna circuit and of the oscillating circuit 22, 23, and 24 are 10 arranged so as to be in resonance and the capacity of the coupling condenser 9 is properly adjusted, the energy of the oscillating circuit, 22, 23, 24 will be gradually transmitted to the antenna circuit which will set 15 it in oscillation and the energy gradually radiated in the form of electromagnetic waves. In these operations, the functions performed by the condenser 9, in the transmitting or sending set, are electrically the 20 same as in the receiving set of a wireless telegraph system, in each instance being a very superior substitute in many respects to the ordinary form of electromagnetic coupling through the employment of the transformer. 25 Referring further to the functions of the small coupling condenser between the two oscillating circuits, the following explanation is made: With a given E. M. F. impressed on one circuit, a variation in the 30 capacity in the coupling condenser 9 will cause a variation in the intensity of the current in the other circuit (the working circuit *b*), though the resonance condition of the circuit *b* is maintained. The changing 35 of the capacity of the coupling condenser 9 also changes the "stiffness" of the system or circuit *b*, the smaller the capacity of the said coupling condenser the greater the stiffness electrically that is given the system or 40 circuit *b*, that is to say, it will be less and less responsive to potentials of frequencies differing from its own electrical periodicity. In practical work dealing with oscillatory currents, the capacity of the coupling condenser 45 9 is so adjusted as to give the desired stiffness, and yet admits the transmission of sufficient current from one circuit to the other. Sometimes a compromise has to be affected, that is to say the intensity of the current to 50 be transmitted may be somewhat sacrificed so as to obtain an extremely stiff electric circuit.

From the foregoing, it is thought that the essential features of the invention will

be readily understood without further 55 description, but it is also to be understood that I do not limit my invention to the specific circuits and applications shown in the drawings, as the same is susceptible of general application as a coupling between separate 60 oscillating circuits employed for any purpose, and various changes in the arrangement of parts and in the use of details may be resorted to without departing from the spirit or sacrificing any of the advantages 65 of the invention.

I claim:

1. A system of receiving wireless signals including a tuned antenna circuit, a second tuned circuit, and an independent condenser 70 of relatively small capacity to the tuning capacities of the said two tuned circuits and arranged to constitute the coupling or link between said two circuits to transmit electrical energy from one to the other. 75

2. A system of distributing oscillating electrical currents including two separate tuned circuits, and an electrostatic coupling connected by leads with said separate circuits, and consisting solely of a condenser 80 of relatively small capacity.

3. The method of transmitting messages by Hertzian waves which consists in generating electric currents in a closed oscillatory circuit, transmitting the alternating difference of potential between two points in said circuit to an open oscillatory circuit having its electrical constants tuned harmonically with said closed circuit, through the medium of an electrostatic coupling circuit and adjusting the capacity of said electrostatic coupling until the wave length in said coupling circuit is so short and weak as to be practically of negligible effect. 85

4. Apparatus for wireless telephony 95 comprising a closed and an open circuit properly tuned to each other, and electrostatic couplings between a pair of points in the one circuit, and a pair of points in the other, each to each, said points in each circuit being electrically distant. 100

In testimony whereof I hereunto affix my signature in the presence of two witnesses.
